Bradford E. Mattes, Esq.; Kleinberg & Lerner, LLP

(57) CLAIM

The ornamental design for a shoe bottom, as shown and described.

DESCRIPTION

FIG. 1 is a perspective view of the shoe bottom showing our new design;

FIG. 2 is a right side elevation view thereof;

FIG. 3 is a left side elevation view thereof;

FIG. 4 is a bottom plan view thereof;

FIG. 5 is a front elevation view thereof; and,

FIG. 6 is a rear elevation view thereof.

The broken lines showing the shoe upper in the figures are for illustrative purposes only and form no part of the claimed design.
